Susius O. Palmer (a/pigno to J. F. Seymour) Utica, N.Y.
Letters Patent (Design No. 95) dated October 10th, 1841,

The schedule referred to in these Letters Patent and making
part of the same.

To all whom it may concern; Be it known that I Susius O. Palmer of the City of Utica in the County of Oneida and State of New York, have invented and produced a new and original design, shape, configuration & pattern of stone plates to be used in the manufacture of stones, the nature of my invention consists in the peculiar form and ornamental carved work of the outer surface of the cast iron plates forming the stone; the feet are of embossed work, which cannot be described in words but is well delineated in the annexed drawing; the bottom plate is carved on the outer edge & surrounded by a plain moulding which runs into ornamental carved & scroll work on the corners at the middle of each of the four sides; in the front side of the stone a paw is sunk in the bottom to give a draft to the stone; this is covered with a piece of iron carved with flowers; the body of the stone is like a common bay stone with double doors on the front side & a door in the side; the side doors are fluted with diamond work between also they are surrounded

by Gothic arches & supported on each side by a representation of Gothic windows, surmounted by Gothic Arches; the top of the body of the stone is formed of successive steps the edges of which are ornamented with embossed work, which cannot be now accurately described but is correctly delineated in the annexed drawing, & the last of which forms the base of the two columns which rest on the top of the body of the stone; these columns are two square in form excepting towards their tops where they curve slightly outwards on all sides; each side of these columns is ornamented with a deeply carved Gothic window with diamond shaped panes; the tops of both of these columns are surrounded by caps, gothic shaped running up into a small pinnacle ornamented with a richly carved leaf on each side; between these two columns rising from over the place from which the smoke escapes into the stone pipe is a Gothic window or arch, fitted with Gothic pinnacles & surmounted with a mullion. The whole of the above description cannot be more accurately given in words, but the whole shape configuration, ornamental work of said stone is accurately delineated in the annexed drawing: What I claim as my invention & desire to secure by Letters Patent is the design, shape, configuration, style & ornamental carvings of the external surface of the plates.
